UNITED STATES PATENT OFFICE.

JOHN WHEATLEY, OF THE ROYAL NAVY, ENGLAND.

IMPROVED SHIP OF WAR.

Specification forming part of Letters Patent No. **39,601**, dated August 18, 1863.

To all whom it may concern:

Be it known that I, JOHN WHEATLEY, captain in the Royal Navy, of No. 9 Giecks strasse, Munich, a subject of the Queen of Great Britain, have invented or discovered new and useful Improvements in the Construction of Ships of War; and I, the said JOHN WHEATLEY, do hereby declare the nature of the said invention and in what manner the same is to be performed to be particularly described and ascertained in and by the following statement thereof—that is to say:

This invention has for its objects improvements in the construction of ships of war. For these purposes in constructing a ship of war according to my invention, I form the bow A with a sharp projecting grub or crab bow at an angle of about twenty-five degrees with the keel, and propel the vessel by paddle-wheels and screw or by screws, the wheels when used working independently, so as to steer the vessel thereby. The rudder is to be supported by chocks, acting like a common vise when under rapid headway. In order to be able to mount guns of large caliber and power—say thirteen inches or fifteen inches and twenty tons weight and upward, smooth-bore—in or near the center of the vessel, as at B, pointing in a line with the keel, I construct a glacis, C, plated over with armor-plates and over the whole fore part of the vessel and extending to the front of the paddle-boxes.

Figure 1 is a plan; Fig. 2, a side view, partly in section; and Fig. 3 is a transverse section taken at the line 1 1, Fig. 1, of the fore part of a war-vessel constructed according to my invention and adapted to be propelled by paddle-wheels acting either in conjunction with a screw or screws or otherwise.

It will be seen that the guns D are placed a little forward of the center of the vessel, where a plated battery is formed, rendered shot-proof by armor-plates, such as shown at E, Fig. 4, or of other kinds. The guns D are mounted on slides b, so as to fire through narrow ports a. They are placed parallel the one to the other, and have no power of training, the guns being laid onto the mark by the steerage of the ship. The form given to the fore part of the ship will cause it on running into another vessel to rise on striking the blow, and then the weight of the ship tends to force under the adverse vessel and will do so if the blow be struck with sufficient power. The armor-plated glacis C will deflect off any shots which may strike it, and will in most cases throw them up clear of the battery, as before mentioned. I employ two screw-chocks, one on each side of the rudder. These, being screwed, will nip or hold the rudder in a central position, or will support it in any desired position under rapid sternway, the chocks being more or less screwed up, as may be required.

What I claim in the construction of ships of war is—

The arrangement of the sharp bow and glacis forward of the center of the ship, so as to admit of the placing and "laying" of the guns by the steerage of the ship, as set forth and shown.

JOHN WHEATLEY.
